(57) **CLAIM**

The ornamental design for reduced footprint computer keyboard, as shown and described.

DESCRIPTION

FIG. 1 is a front side perspective view of a reduced footprint computer keyboard showing the design;

FIG. 2 is a top plan view thereof;

FIG. 3 is a bottom plan view thereof;

FIG. 4 is a rear elevational view thereof;

FIG. 5 is a front elevational view thereof;

FIG. 6 is a right side elevational view thereof; and,

FIG. 7 is a left side elevational view thereof.

The broken lines are shown in the views for illustrative purposes only and form no part of the claimed design.
